UNITED STATES PATENT OFFICE.

HENRY C. MUSTIN, OF THE UNITED STATES NAVY.

WATER-BRAKE ATTACHMENT FOR HYDRAEROPLANES.

1,160,525.

Specification of Letters Patent. Patented Nov. 16, 1915.

Application filed February 18, 1915. Serial No. 9,096.

To all whom it may concern:

Be it known that I, HENRY C. MUSTIN, lieutenant commander, United States Navy, a citizen of the United States, stationed at Washington, in the District of Columbia, have invented certain new and useful Improvements in Water-Brake Attachments for Hydraeroplanes; and I do hereby declare the following to be a full, clear, and exact description of the invention, such as will enable others skilled in the art to which it appertains to make and use the same.

My present invention relates to improvements in water brake attachment for hydraeroplanes, or that class of aeroplane which is adapted for finishing its flight on water, or for beginning its flight therefrom.

It has been found from experience that in alighting on the water after flight with such a machine, there are certain difficulties to be encountered, some of which amount to positive danger, not only to the apparatus, but to the life of the aviator, and others which are more or less serious, and it is the object of this invention to obviate these as far as practicable, and to provide an apparatus by which the aeroplane may be brought to rest upon the water without injury to itself, or to its occupants, and irrespective of the nature of the surface of the water, or of currents of air blowing at an angle to the vertical plane in which the longitudinal axis of the aeroplane lies, or in which the aeroplane may be said to be "heading."

Among the functions to be performed by the water brake attachment are the following:

(1). Before the pontoons or flotation members make contact with the water, it is desirable to retard the speed of flight, by applying, without violence, at a point in rear of the center of gravity of the aeroplane, such a vertical downward component of the pull on the water brake connection as will cause the nose of the aeroplane to tilt up, or will rotate the aeroplane about its transverse axis of inertia in such a direction as will make the lifting surface assume a larger angle of incidence, and consequently will make it increase its head resistance. This force component should be applied, preferably, in such a manner that the center of gravity of the aeroplane will not rise materially; and, also, that the center of gravity

of the aeroplane will not settle materially until the speed of flight has fallen to the lowest speed of sustentation that the design of the aeroplane makes it capable of maintaining.

(2). Coincident with the application of the above-mentioned vertical component, it is desirable to apply a brake-like action to further retard the speed of flight by applying a horizontal component of the pull on the water brake connection, which drags backward in a direction opposed to the line of flight.

These first two functions are for the purpose of reducing the violence of impact when the pontoons or flotation members of the aeroplane make contact with the waves at the end of a flight over a rough sea.

(3). When air currents are blowing across the vertical plane in which the aeroplane is heading, the aeroplane will have a lateral motion relative to the water, generally known as "skidding," and the velocity of which lateral motion will depend upon the force and direction of the horizontal component of the air currents relative to the vertical plane in which the aeroplane is heading. Of course, when the flotation members dip down into the water while the aeroplane is skidding, there will be a tendency not only to wrench off the flotation members from the aeroplane, but also to cause the aeroplane to capsize; and it is desirable, therefore, to have these flotation members cut into the water, as near as possible, in a vertical plane or planes parallel to the vertical plane comprising the true trajectory of the aeroplane, irrespective of the angle to which these flotation members may be tilted fore and aft, due to the tilting of the longitudinal axis of the aeroplane. It is desirable, therefore, to apply the drag or brake so that the aeroplane will head as nearly as practicable in line with its true trajectory.

(4). When the aeroplane lands in water that is rough enough to cause the forward ends of the flotation members to dip into the crest of the wave, there is a tendency of the aeroplane to tilt forward, or "nose under" as it is sometimes called, or even to turn over about its transverse axis, throwing out the occupants and endangering the machine. It is desirable, therefore, to insure

that the contact of the flotation members of the aeroplane with the water will be made and maintained at a point or points in rear of the center of gravity of the aeroplane before it is made at a point or points forward of the center of gravity.

(5) When the aeroplane lands in the water at a very high speed, as, for example, when landing with the wind (which is sometimes unavoidable and sometimes even desirable) there is danger of nosing under, due to the excessive drag of the water on the pontoons, causing the center of gravity of the aeroplane to tilt forward and downward.

(6) Where the pontoons or floating members are used in pairs, when due to the tilting of the transverse axis of the aeroplane, or due to irregularities in the waves, one of the pontoons strikes the water before the other, there is a tendency to swing the longitudinal axis of the aeroplane about the vertical axis of inertia of the aeroplane, resulting in what is sometimes called "yawing," and if this yawing is at all aggravated the aeroplane may be capsized.

These are the principal difficulties encountered in alighting on the water with a hydraeroplane, and it is to remedy these difficulties, and others of less importance, that I have provided the apparatus that will now be described.

Reference is had to the accompanying drawings, in which:—

35 Fig. 1 is a diagrammatic view showing in side elevation the aeroplane with the brake attachment thrown out and ready for alighting on the water; Fig. 2 is a front elevation of the device shown in Fig. 1; Fig. 3 is a similar view to Fig. 1, showing the brakes in action; Figs. 4 and 5 represent, respectively, a plan and elevation of the water brake attachment and parts of its tow line in action in the water; the direction of motion being from left to right; Fig. 6 shows in perspective, parts being broken away, the upper and lower brakes secured together in a position suitable for storage in the hydraeroplane, and for towing in the air in such manner that the bridles and their connecting cable will not become twisted or entangled with any part of the brake; Fig. 7 is a cross section, on an enlarged scale, through the two brakes along the line 6—6 of Fig. 6, and shows a method of coupling the two brakes together; and Fig. 8 shows a section along the line 8—8 of Fig. 6 on an enlarged scale, and shows a method of detachably connecting the tow rope or cable and bight of the bridle to the upper member of the brake for keeping same from becoming entangled when the device is carried in the aeroplane, or is being towed in air.

65 The invention is adapted for use with any

type of aeroplane, whether monoplane, biplane, or the like, and also irrespective of whether the pontoons be used singly or in pairs, or in any other arrangement, or number.

To illustrate the application of the device I have shown diagrammatically in Figs. 1, 2 and 3 a simple form of aeroplane comprising a monoplane A, having a pair of front pontoons B, and a rear and smaller pontoon B'; the center of gravity of the aeroplane with its load being indicated by the circle C.

D represents a tow line, preferably in the form of a light wire cable, which terminates in a main bridle D' having two branches d and d', each connected by secondary bridles d² and d³, respectively, to the corresponding brakes E and E'. These secondary bridles (see Fig. 5) are preferably connected to the wings e³ and e⁴, preferably on transverse lines including, respectively, the centers of pressure of the wings, and tend to brace the same, and also to stabilize the brake members. This tow rope D should be connected to the body of the aeroplane by a yielding connection, such as a stout coil spring indicated at S in Figs. 1, 3 and 4, or the usual type of rubber springs used in aeroplanes may be employed; or it may be wound on a friction drum, not shown, which will pay out the cable when the strain becomes excessive. Such drums are well known in the various arts, and it is not believed to be necessary to illustrate and describe same herein; but any suitable yielding means may be provided to prevent excessive shock on the aeroplane when the brake first takes the water, or when being dragged from wave to wave in a heavy sea.

105 The two brakes E and E' are substantially similar in construction, both having preferably a stream-line shaped body portion, as shown, but the lower brake E' should be heavier than sea water, and the upper brake E should have reserve buoyancy so as to float in water, whether fresh or salt. This is desirable to insure the normal tendency of the two members to adapt themselves to positions in the same vertical plane. Each 110 brake is provided with similar vertical stabilizing fins e and e', corresponding to the dorsal fins of a fish, with a horizontal stabilizing tail e², and with laterally-projecting 115 brake wings e³ and e⁴. These brake wings may 120 be plane, or curved, on either, or both sides, as desired, but are preferably plane on the engaging surface and curved on their backs, as shown in Figs. 5 and 6; the brake wing on the upper brake E having its engaging 125 face tilted upward and forward, so as to provide an angle of incidence with the water tending to lift the said brake, and the brake wing on the lower brake having its engaging face tilted downward and forward, so as to 130

provide an angle of incidence tending to submerge the brake E' in the water.

The relative sizes of the two brake wings may be varied also, but I preferably make the brake wing on the lower brake with a greater engaging surface than the brake wing on the upper brake, so that when both members engage beneath the surface there will be a tendency of the lower member to 10 drag down, owing to the increased pressure area of its brake wings; then the downward drag on the tow line will be equal to the difference in lifts (vertical forces) of the two brake wings. A similar result may be 15 secured by making the angle of incidence of the lower brake wings e^4 greater than the angle of incidence of the upper brake wings e^3 . If, for any reason, it is desired to prevent the submersion of the upper brake E, 20 its brake wings may be of greater engaging surface than the brake wings of the lower brake, or the angle of incidence of its brake wings may be made greater, whereby the lower brake E' may be submerged while the 25 upper brake E skims along the surface of the water.

The lifting action of the tow rope, of course, tends to pull both of the brake members upward out of the water, which is resisted by the wedging downward action of the brake wings on the lower brake E', and is assisted in a measure by the lifting action of the brake wings on the upper brake E. These two brake members E and E' are 35 preferably secured or folded together when being carried on the aeroplane, or when being towed through the air, as shown in Figs. 1, 6 and 7, both to economize space, and to keep the towing cable and bridle clear; but 40 are automatically spread out when engaging with the water, as shown in Figs. 4 and 5.

Referring to Figs. 1, 6, 7 and 8, the upper brake E is provided with a socket e^6 , chambered, as at e^7 , to receive the spring grip e^8 , 45 which spring grip engages the longitudinal grooved head e^9 of the forward stabilizing fin e of the lower brake E'; while the bottom of the tail of the upper brake E rests on the rear stabilizing fin e' of the lower 50 brake E', as shown in Fig. 6.

The tow rope and bridle may be detachably connected to the brake E in any convenient way, as by engaging in spring jaws E secured to the body portion of the brake 55 member aforesaid, as shown in detail in Fig. 8. The tow rope D is fastened to the aeroplane in rear of the center of gravity, and in such a position that it will pull the tail of the aeroplane downward when the 60 brakes are in operation, and should be at least long enough so that when towing in the air, the brakes will be well below the bottoms of the pontoons. When ready for use, they are eased out of the aeroplane and 65 assume a position similar to that shown in

Fig. 1, and on striking the water the increased resistance will cause the tow rope and bridle to pull out of engagement with the spring clips F, and will also cause the release of the fin e of the lower brake from 70 the spring clip e^8 , see Fig. 7, whereupon the parts are free to assume the position shown in Figs. 4 and 5.

The operation of the device is as follows:—The apparatus is ordinarily stored 75 in any convenient place on the aeroplane, preferably in rear of the operator, and when it is desired to land on the water the tow rope is eased out, either by hand, or by the friction drum hereinbefore referred to, so 80 that by the time the aeroplane has flattened out at the end of a glide, the parts are in the position shown in Fig. 1. As the aeroplane settles slightly farther, the lower 85 brake E' will strike the water, disengaging itself from the upper brake E, and the two brakes will spread out as shown in Fig. 5, riding to the bridle D'. The sudden pull occasioned when the brake attachment first 90 engages the water will be eased up by the shock absorber S. In a choppy sea, should the upper brake momentarily emerge from the surface, the downward thrust of the lower brake wing, instead of being partly compensated for by the lift of the upper 95 brake wing, will act singly, tending to cause the lower brake to dive; and preventing the upward lift of the tow line from dragging it out of water.

The device can be so designed, that the 100 lifting power of the aeroplane can never exceed the downward drag of the lower brake. If the aeroplane is heading directly into or with the direction of the wind, it will merely have its tail tilted down, as 105 shown in Fig. 3, and will proceed ahead on the original course; but if it is proceeding in a side wind and consequently is not heading in line with its trajectory, the result of the drag will also cause the bow of the aeroplane to swing around through an angle dependent upon the force and direction of the wind, and make it bend in its trajectory. The pulling down of the tail of the aeroplane will increase the angle of incidence 110 of the wings thereof, and, therefore, by increasing the drift, will check the forward movement of the aeroplane.

The increasing of the angle of incidence, besides increasing the drift, also increases 115 the lift, and while the excess lift remains greater than the downward force component on the tow line the aeroplane will rise. But as the brake can be designed so that its lower member cannot be pulled out of the water 120 by this excess lift, there can be no excessive rearing of the aeroplane. The speed then is further reduced by the drag on the tow line; and, finally the speed of the aeroplane 125 is so slowed down that it settles in the water 130

with its tail inclined downward, and its pontoons in the proper attitude for a safe landing. The result of this action is that all of the difficulties set out in the paragraphs numbered 1-6 of this specification are in a large measure overcome.

The device may be adapted for use on large or small aeroplanes by varying the size, or the angles of incidence, of the brake

10 wings e^3 and e^4 .

After the hydraeroplane has landed on the water, the tow line should be hauled in, and the brake attachment stowed on board. In exceptional cases, the brake attachment 15 may be used, if desired, as a drogue while the hydraeroplane is being propelled along the surface of the water; but ordinarily it should be hauled in before attempting to make a fresh start in the air or on the water.

20 It will be obvious that various modifications might be made in the herein described device and in the construction, combination and arrangement of parts which could be used without departing from the spirit of 25 my invention.

Having thus described my invention, what I claim and desire to secure by Letters Patent of the United States is:—

1. A brake attachment for hydraeroplanes, comprising a water brake adapted to 30 be drawn through the water, and provided with a body portion and laterally projecting wing surfaces so arranged that their lift forces, caused by motion through the water, 35 act in opposite directions vertically.

2. A brake attachment for hydraeroplanes, comprising a water brake adapted to be drawn through the water, and provided 40 with a body portion and laterally projecting wing surfaces so arranged that their lift forces, caused by motion through the water, act in opposite directions vertically, with means for stabilizing said wing surfaces.

3. A brake attachment for hydraeroplanes, comprising a water brake adapted to 45 be drawn through the water, and provided with wing surfaces so arranged that their lift forces, caused by motion through the water, act in opposite directions vertically, 50 said wing surfaces being so proportioned that their downward lift forces are in excess of their upward lift forces.

4. A brake attachment for hydraeroplanes, comprising a water brake adapted to 55 be drawn through the water, and provided with wing surfaces so arranged that their lift forces, caused by motion through the water, act in opposite directions vertically, 60 said wing surfaces being so proportioned that their downward lift forces are in excess of their upward lift forces, with means for stabilizing said wing surfaces.

5. The combination with an aeroplane of 65 a water brake adapted to be drawn through the water by said aeroplane, said water

brake being provided with wing surfaces so arranged that their lift forces, caused by motion through the water, act in opposite directions vertically, and means for connecting said brake to said aeroplane at such point on the latter as will cause the aeroplane's wings to assume an increased angle of incidence when said brake engages the water.

6. The combination with an aeroplane of 75 a water brake adapted to be drawn through the water by said aeroplane, said water brake being provided with wing surfaces so arranged that their lift forces, caused by motion through the water, act in opposite 80 directions vertically, with means for stabilizing said wing surfaces, and means for connecting said brake to said aeroplane at such point on the latter as will cause the aeroplane's wings to assume an increased 85 angle of incidence when said brake engages the water.

7. An attachment for hydraeroplanes, comprising separable brakes detachably connected together, with brake wings projecting 90 from each of said brakes, said brake wings being each provided with engaging surfaces adapted to engage the water at an angle, and means for connecting said brakes to the aeroplane.

8. An attachment for hydraeroplanes, comprising separable brakes detachably connected together, with brake wings projecting from each of said brakes, said brake wings being each provided with engaging 95 surfaces adapted to engage the water at an angle, and means for connecting said brakes to the aeroplane, with a shock absorber interposed between said brakes and said aeroplane.

9. An apparatus for braking aeroplanes, comprising separable brakes, each provided with a body portion and with laterally extending brake wings, the said brake wings each having surfaces adapted to engage the water at an angle, a bridle connecting said brakes, and a tow line connecting said bridle with the aeroplane.

10. An apparatus for braking aeroplanes, comprising separable brakes, each provided with a body portion and with laterally extending brake wings, the said brake wings having surfaces adapted to engage the water at an angle, a bridle connecting said brakes, and a tow line connecting said bridle with the aeroplane, with a shock absorber interposed between said brakes and said aeroplane.

11. An attachment for hydraeroplanes, comprising a tow line adapted to be secured to the aeroplane, two separable brake members loosely connected to each other and to said tow line, stabilizing fins projecting from each of said brake members, and brake wings projecting from each of said brake

members and provided with engaging surfaces adapted to engage the water at different angles.

12. An attachment for hydraeroplanes, comprising a tow line adapted to be secured to the aeroplane, two separable brake members loosely connected to each other and to said tow line, vertical stabilizing fins projecting from each of said brake members, and brake wings projecting from each of said brake members provided with engaging surfaces adapted to engage the water at different angles.

13. An attachment for hydraeroplanes, comprising a tow line adapted to be secured to the aeroplane, two separable brake members loosely connected to each other and to said tow line, vertical stabilizing fins and a horizontal stabilizing tail projecting from each of said brake members, and brake wings projecting from each of said brake members provided with engaging surfaces adapted to engage the water at different angles.

14. An attachment for hydraeroplanes, comprising a tow line adapted to be secured to the aeroplane, two separable brake members loosely connected to each other and to said tow line, stabilizing fine projecting from each of said brake members, and brake wings projecting from each of said brake members provided with engaging surfaces adapted to engage the water at different angles, with a shock absorber interposed between said brake members and said aeroplane.

15. An attachment for hydraeroplanes, comprising a tow line adapted to be secured to the aeroplane, two separable brake members loosely connected to each other and to said tow line, vertical stabilizing fins projecting from each of said brake members, and brake wings projecting from each of said brake members provided with engaging surfaces adapted to engage the water at different angles, with a shock absorber interposed between said brake members and said aeroplane.

16. An apparatus for braking aeroplanes, comprising two separable brakes, each provided with stabilizing fins and brake wings, the said brake wings having surfaces adapted to engage the water at different angles, a bridle connecting said brakes, and a tow line connecting said bridle with the aeroplane.

17. An apparatus for braking aeroplanes, comprising two separable brakes, each provided with stabilizing fins and brake wings, the said brake wings having plane engaging surfaces adapted to engage the water at different angles, a bridle connecting said brakes, and a tow line connecting said bridle with the aeroplane.

18. An apparatus for braking aeroplanes, comprising two separable brakes, each pro-

vided with stabilizing fins and with brake wings, the said brake wings having surfaces adapted to engage the water at different angles, a bridle connecting said brakes, and a tow line connecting said bridle with the aeroplane, with a shock absorber interposed between said brakes and said aeroplane.

19. An apparatus for braking aeroplanes, comprising two separable brakes, each provided with stabilizing fins and brake wings, the said brake wings having plane engaging surfaces adapted to engage the water at different angles, a bridle connecting said brakes, and a tow line connecting said bridle with the aeroplane, with a shock absorber interposed between said brakes and said aeroplane.

20. An attachment for hydraeroplanes, comprising a tow line adapted to be secured to the aeroplane, and two separable brakes having stream-line body portions loosely connected to each other and to said tow line, with brake wings projecting from each of said body portions, said wings being provided with engaging surfaces adapted to engage the water at different angles.

21. An attachment for hydraeroplanes, comprising a tow line adapted to be secured to the aeroplane, and two separable brakes having stream-line body portions loosely connected to each other and to said tow line, with stabilizing fins and brake wings projecting from each of said body portions, said wings being provided with engaging surfaces adapted to engage the water at different angles.

22. An attachment for hydraeroplanes, comprising a tow line adapted to be secured to the aeroplane, and two separable brakes having stream-line body portions loosely connected to each other and to said tow line, with brake wings projecting from each of said body portions and provided with engaging surfaces adapted to engage the water at different angles of incidence, with a shock absorber interposed between said brakes and said aeroplane.

23. An attachment for hydraeroplanes, comprising a tow line adapted to be secured to the aeroplane, and two separable brakes having stream-line body portions loosely connected to each other and to said tow line, with stabilizing fins and brake wings projecting from each of said brakes and said brake wings being provided with engaging surfaces adapted to engage the water at different angles, and with a shock absorber interposed between said brakes and said aeroplane.

24. An apparatus for braking aeroplanes, comprising two separable brakes having stream-line body portions, each provided with brake wings, the said brake wings having surfaces adapted to engage the water at different angles, a bridle connecting said

brakes, and a tow line connecting said bridle with the aeroplane.

25. An apparatus for braking aeroplanes, comprising two separable brakes having stream-line body portions, each provided with stabilizing fins and brake wings, the said brake wings having surfaces adapted to engage the water at different angles, a bridle connecting said brakes, and a tow line connecting said bridle with the aeroplane.

26. An apparatus for braking aeroplanes, comprising two separable brakes having stream-line portions, each provided with brake wings, the said brake wings having surfaces adapted to engage the water at different angles, a bridle connecting said brakes, and a tow line connecting said bridle with the aeroplane, with a shock absorber inter-

posed between said brakes and said aeroplane.

27. An apparatus for braking aeroplanes, comprising two separable brakes having stream-line body portions, each provided with stabilizing fins and brake wings, the said brake wings having surfaces adapted to engage the water at different angles, a bridle connecting said brakes, and a tow line connecting said bridle with the aeroplane, with a shock absorber interposed between said brakes and said aeroplane.

In testimony whereof, I affix my signature, in presence of two witnesses.

HENRY C. MUSTIN.
